US00D967017S

(12) **United States Design Patent** (10) **Patent No.:** **US D967,017 S**
Jun et al. (45) **Date of Patent:** **** Oct. 18, 2022**

(54) **CHARGER FOR ELECTRONIC DEVICE**

- (71) Applicant: **Samsung Electronics Co., Ltd.**, Suwon-si (KR)
- (72) Inventors: **Youngjoong Jun**, Suwon-si (KR); **Jinwook Kim**, Suwon-si (KR); **Syeon Lee**, Suwon-si (KR)
- (73) Assignee: **Samsung Electronics Co., Ltd.**, Suwon-si (KR)
- (**) Term: **15 Years**
- (21) Appl. No.: **29/699,038**
- (22) Filed: **Jul. 23, 2019**
- (30) **Foreign Application Priority Data**

- Jan. 31, 2019 (KR) 30-2019-0004991
- (51) **LOC (13) Cl.** **13-02**
- (52) **U.S. Cl.**

(57) **CLAIM**

We claim the ornamental design for a charger for electronic device, as shown and described.

DESCRIPTION

FIG. 1 is a front perspective view of a charger for electronic device showing our new design;
FIG. 2 is a front view thereof;
FIG. 3 is a rear view thereof;
FIG. 4 is a left-side view thereof;
FIG. 5 is a right-side view thereof;
FIG. 6 is a top view thereof;
FIG. 7 is a bottom view thereof;
FIG. 8 is a cross-sectional view thereof taken through line 8-8 in FIG. 2;
FIG. 9 is a cross-sectional view thereof taken through line 9-9 in FIG. 2; and,
FIG. 10 is a top view thereof, shown in an environment of use.

The broken lines in the figures showing portions of the charger for electronic device form no part of the claimed design.

The broken lines shown in FIG. 10 depict environmental subject matter that forms no part of the claimed design.

1 Claim, 10 Drawing Sheets
